UNITED STATES PATENT OFFICE.

OLIVER HUGHES, OF NEW CAMBRIA, MISSOURI.

RAILWAY-TIE.

SPECIFICATION forming part of Letters Patent No. 733,843, dated July 14, 1903.

Application filed April 18, 1903. Serial No. 153,317. (No model.)

To all whom it may concern:

Be it known that I, OLIVER HUGHES, a citizen of the United States, residing at New Cambria, in the county of Macon and State of Missouri, have invented new and useful Improvements in Railway-Ties, of which the following is a specification.

My invention relates to new and useful improvements in railway-ties; and its object is to provide a tie of this character which is provided with novel means for fastening rails thereto.

A further object is to employ ties the ends of which are constructed so as to securely join the adjacent abutting ends of rails and prevent pounding upon said ends by the wheels of a car passing thereover.

With the above and other objects in view the invention consists in providing metal rail-road-ties the ends of which are bent inward and adapted to extend over the outer flanges of the rails. Securing-plates are detachably fastened to these ties and are adapted to extend over the inner flanges of the rails, and thereby prevent displacement thereof. The ties which extend under the abutting ends of the rails are provided with supporting-blocks which are adapted to extend over the outer fish-plates flush with the upper surface of the heads of the rails. Each of these blocks is secured to the rails by means of bolts, and said bolts also serve to fasten the inner fish-plates in position. As the blocks are flush with the upper surface of the rails, it is obvious that they will serve to support the wheels of a car when passing over the ends of the rails, and will therefore prevent pounding.

The invention also consists in the further novel construction and combination of parts hereinafter fully described and claimed, and illustrated in the accompanying drawings, showing the preferred form of my invention, and in which—

Figure 1 is a plan view of rails mounted upon ties constructed in accordance with my invention. Fig. 2 is a section on line *x-x* of Fig. 1, and Fig. 3 is a section on line *y-y* of Fig. 2.

Referring to the figures by numerals of reference, 11 are railway-ties, each of which is preferably formed of two strips of metal 2 and 3, respectively, the base-strip 2 being secured

to the upper strip 3 in any suitable manner, as by means of bolts 4 extending therethrough. The ends of the upper strip 3 of each tie are 55 bent inward to form hooks 5, adapted to extend over the outer flanges 6 of the rails 7. Securing-plates 8 overlap the inner flanges 9 of the rails and are held securely in position thereover by means of the bolts 4, which extend therethrough. Ties of special construction are provided at points under the rail-joints. These specially-constructed ties, as illustrated in Fig. 2, are substantially similar to the ordinary ties employed, with the exception that one of the ends of the upper strip 3 terminates in an upwardly-extending block 10, the upper edge of which bears against and is flush with the outer faces of the contacting ends of the rails. This block extends over 60 the outer fish-plate 11 and is clamped thereupon and upon the rails by means of bolts 12, which also serve to secure the inner fish-plate 13 in position. A securing-plate 8 similar to the one hereinbefore described is fastened 65 upon the upper strip 3 of the tie in such position as to allow it to overlap the inner flanges of the rail and the flange of the inner fish-plate. 70

It will be seen that this improved tie is extremely simple and inexpensive in construction, and by the use thereof it is unnecessary to employ spikes or other similar securing means for holding the rails in position. Moreover, spreading of the rails is prevented, and 85 as the upper edge of block 10 is flush with the upper surface of the contacting ends of the rails it is obvious that pounding upon said ends by the wheels of a car passing thereover will be prevented. 90

In the foregoing description I have shown the preferred form of my invention; but I do not desire to limit myself thereto, as I am aware that minor changes may be made therein without departing from the principle or 95 sacrificing any of the advantages thereof, and I therefore reserve the right to make such changes as fairly fall within the scope of my invention.

Having thus described the invention, what I claim as new is—

In combination, a railway-tie comprising a base-plate, an upper strip secured thereto, rails mounted on said upper strip, fish-plates;

said upper strip having one end portion bent inwardly to form a hook adapted to extend over the outer flange of a rail, the opposite end portion of the strip terminating in an upwardly-extending block, the upper edge of which bears against and is flush with the outer faces of the contacting ends of rails, said block extending over an outer fish-plate and clamped thereupon and upon the rails,

and plates secured to the upper strip and over- 10 lapping the inner flanges of the rails.

In testimony whereof I affix my signature in presence of two witnesses.

OLIVER HUGHES.
